CLAIM

The ornamental design for a decorative scarab novelty, as shown and described.

DESCRIPTION

FIG. 1 is a front perspective view of the embodiment of the decorative scarab novelty.

FIG. 2 is a front view of the embodiment of the decorative
scarab novelty;

FIG. 3 is a rear view of the embodiment of the decorative
scarab novelty;

FIG. 4 is a left-side view of the embodiment of the decorative
scarab novelty;

FIG. 5 is a right-side view of the embodiment of the decorative
scarab novelty;

FIG. 6 is a top view of the embodiment of the decorative scarab novelty; and,

FIG. 7 is a bottom view of the embodiment of the decorative
scarab novelty.

The dashed lines showing in the figures are included for the purpose of illustrating portions of the decorative scarab
novelty that form no part of the claimed design.

1 Claim, 5 Drawing Sheets
